US0D1070702S

(12) **United States Design Patent** (10) **Patent No.:** **US D1,070,702 S**
(45) **Date of Patent:** **** Apr. 15, 2025**

(54) **RUNNING BOARD**

(71) Applicant: **Wenzhou Shangnuo Information Technology Co., Ltd.**, Wenzhou (CN)
(72) Inventor: **Xiaotong Zhao**, Ruian (CN)
(73) Assignee: **Wenzhou Shangnuo Information Technology**, Wenzhou (CN)

(**) Term: **15 Years**

(21) Appl. No.: **29/880,600**

(22) Filed: **Jul. 25, 2023**

(51) LOC (15) Cl. **12-16**
(52) U.S. Cl. ....

USPC **D12/203**

(58) **Field of Classification Search**

USPC D12/89, 98, 162, 190, 196, 203, 314;

(57) **CLAIM**

The ornamental design for a running board, as shown and described.

DESCRIPTION

FIG. 1 is a top perspective view of a running board, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the running board, which form no part of the claimed design.

1 Claim, 8 Drawing Sheets
